DESIGN FOR AN ILLUMINATED COIN CONTROLLED MACHINE CASING

James G. Wells, Chicago, Ill.

Application February 3, 1936, Serial No. 60,954

Term of patent 3½ years

To all whom it may concern:

Be it known that I, James G. Wells, a citizen of the United States, residing at 2770 Potwein Street, Chicago, in the county of Cook and State of Illinois, have invented a new, original, and ornamental Design for an Illuminated Coin Controlled Machine Casing, of which the following is a specification, reference being had to the accompanying drawing, forming part thereof.

The single figure of the drawing is a perspective view of the illuminated coin controlled machine casing showing my new design.

The side or face of the casing (not shown) which lies opposite the face shown at the lower right of the figure of the drawing is ornamented like the latter face.

I claim:

The ornamental design for an illuminated coin controlled machine casing, as shown and described.

JAMES G. WELLS.
